(57) **CLAIM**

The ornamental design for a charger, as shown and described.

DESCRIPTION

FIG. 1 is a perspective view of the front and left side of the charger according to our new design.

FIG. 2 is a front view of the charger of FIG. 1.

FIG. 3 is a rear view of the charger of FIG. 1.

FIG. 4 is a left side view of the charger of FIG. 1.

FIG. 5 is a right side view of the charger of FIG. 1.

FIG. 6 is a top view of the charger of FIG. 1; and,

FIG. 7 is a bottom view of the charger of FIG. 1.

The charger is shown with a symbolic break in its length. The appearance of any portion of the article between the break lines forms no part of the claimed design. The broken lines shown in the drawings are included for the purpose of illustrating unclaimed portions of the charger, and form no part of the claimed design.

(Continued)

The ornamental design of the present disclosure is a charger for use in charging an activity tracker module.
